AU 291

E

OF D 15,285

Design No. 15,285, dated August 19, 1884.

UNITED STATES PATENT OFFICE.

NICHOLAS STEFFENS, OF NEW YORK, N. Y.

DESIGN FOR A FLOWER-FRAME.

SPECIFICATION forming part of Design No. 15,285, dated August 19, 1884.

Application filed July 3, 1884. Term of patent 7 years.

To all whom it may concern:

Be it known that I, NICHOLAS STEFFENS, a citizen of the United States, residing at New York, in the county and State of New York, have originated and produced a new Design 5 for Flower-Frames, of which the following is a specification.

The drawing is a perspective of my newly-designed flower-frame.

10 A is a cross; B, a crown; and C C are branches. The cross A, as shown in the drawing, is of rectangular section. Its lower part projects through the inner hollow part of the crown B, and is set at an inclination. The 15 crown B is designed with a circular or elliptical base, and is provided with peaks. The

crown B abuts against the lower part of the cross. From the crown B spring branches C C, bearing leaves, and crossing each other, substantially as represented in the drawing. 20

I claim—

The design for a flower-frame, substantially as herein shown and described, the same consisting of the cross A, the crown B, and branches C C.

25 In testimony whereof I have hereunto set my hand and seal in the presence of two subscribing witnesses.

NICHOLAS STEFFENS. [L. S.]

Witnesses:

W. HAUFF,

E. F. KASTENHUBER.
